WALTER RÜDIGER, OF BERLIN-KARLSHORST, GERMANY, ASSIGNOR TO TELEPHON-APPARAT FABRIK E. ZWEITUSCH AND COMPANY, OF BERLIN, GERMANY

DAMP-PROOF CONDENSER

Application filed November 21, 1928, Serial No. 320,828, and in Germany March 22, 1928.

The present invention relates in general to moisture proof containers for electrical apparatus such as condensers, and the principal object of the invention, briefly stated, is the production of a new and improved moisture proof container suitable for use under extreme conditions such as are encountered in the tropics.

It is known that the insulation resistance is greatly reduced when mere traces of dampness enter the condenser. The condenser coils which are sealed with paraffin and fitted into casings which are then filled up with a material of the asphalt type in the usual manner, are not the best for use in the tropics, because they do not comply with the more stringent requirements as regard damp-proofness. Also that type of filling is often destroyed by insects. In order to obtain an effective closure, it is therefore necessary to use a metal covering lid for condensers to be used in the tropics this lid being placed on the casing and then soldered to it. There is difficulty in insulating the leading-in wires from the covering lid, owing to the stricter requirements as regards damp-proofness. It has been proved that even accurately fitting insulating bushes do not meet the requirements.

The present invention enables the conductors to be taken through the metal casing without there being the least danger of dampness penetrating into the condenser through the part where the leads pass through. There is the further advantage that this method of passing through the leads can conveniently be adopted on a manufacturing scale, so that the method according to the invention is considerably cheaper than that hitherto used for taking the leads through. These advantages are obtained by embedding the leading-in wires in insulating material of any known kind which can be pressed into any desired shape. Material having this adaptability as regards shape is best for the present purpose, because it fits tight into all uneven parts of the leading through points to be closed up, and after pressing has been done, it forms a rigid binding between the condenser casing and the soldering tags.

In Figs. 1 to 3 is shown a method of car-

rying out the invention. Fig. 1 shows a condenser casing seen in front elevation; Fig. 2 shows it in plan; Fig. 3 shows a side elevation partially in section.

The soldering tags 1 and 2 forming the metal connections pass through the cap 3 of the casing and are insulated therefrom. As can be seen from Fig. 3, the metal cap 3 of the condenser has a folded edge 6 at the leading through point, so that the insulating material 4, which is pressed into the cap, can shrink tight onto the cap. A zigzag shape is given to the part of the soldering tags 1 and 2 where they are embedded in the insulating material in order to increase the creep path for the damp and also to give the soldering tags a firm hold in the insulating material. The cap 3 is inserted in the casing 5 and secured to it by soldering them together.

What is claimed is:

A container for electrical equipment having a cover comprising a cup-shaped metal body having its sides secured to said container and having a centrally located aperture the edges of said aperture being bent inward and then parallel to the surface of said body, terminal pieces projecting through said aperture and molded insulating material binding said terminal pieces and said body into a rigid unitary structure, said insulating material entirely encasing said bent edges to form a long creep path for moisture.

In witness whereof, I hereunto subscribe my name this 23rd day of October, A. D. 1928.

WALTER RÜDIGER.
